VENTILATING MECHANISM FOR TOILET BOWLS

Otto R. Oehring, Saginaw, Mich.

Application October 14, 1944, Serial No. 558,763

2 Claims. (Cl. 4—213)

1

This invention relates to an improved ventilating mechanism for toilet bowls and the like. More specifically the invention embraces an attachment which can be applied to toilet bowls already in use, as well as to new bowls in the process of manufacture.

One of the prime objects of the invention is to design a ventilating attachment in such form that it can be mounted on and is capable of attachment to the conventional toilet bowl without change or modification of the bowl, or the operating mechanism thereof.

Another object is to design a very simple, practical and comparatively inexpensive attachment which will, when in operation, effectively and efficiently remove all odors from the toilet bowl, and which is automatic in its operation.

A further object is to provide a unitary ventilating device of neat and pleasing appearance, which can be attached, in operative connection, to any suitable bowl with a minimum of labor, and which is secured in position by the conventional seat bolts which form a part of the conventional installation.

A further object still is to provide a gate in the device for controlling the air passage in the unit, to the end that suction occurs only in the bowl or bowls in use and without affecting other bowls connected to the common exhaust pipe.

With the above and other objects in view, the present invention consists in the combination and arrangement of parts, hereinafter more fully described, illustrated in the accompanying drawings, and more particularly pointed out in the appended claims, it being understood that changes may be made in the form, size, proportions and minor details of construction, without departing from the spirit, or sacrificing any of the advantages of the invention.

In the drawings:

Fig. 1 is a fragmentary side elevational view of a conventional toilet bowl with my improved ventilating attachment in place thereon, the seat and cover being omitted.

Fig. 2 is a top plan view with the seat and cover included.

Fig. 3 is an enlarged side elevational view of the attachment proper, the broken lines showing the switch control member forced inwardly to energize the exhaust fan, and actuate the gate, the solid lines showing the plunger and gate in normal position, the arrows indicating the direction of flow of air.

Fig. 4 is an enlarged top plan view.

Fig. 5 is a front elevational view.

2

Fig. 6 is an enlarged view of the linkage for connecting the actuating lever and gate, the broken lines illustrating the movement.

Fig. 7 is an enlarged fragmentary side elevational view of the front end of the unit.

Fig. 8 is a view similar to Fig. 1 and showing an alternate arrangement in which the exhaust fan is automatically energized when the seat is depressed.

Referring now more particularly to the drawings in which I have shown the preferred embodiment of my invention, there is shown in Figs. 1 and 2 a conventional toilet bowl 8, the seat and cover 9 and 10 respectively, being omitted from Fig. 1 to more clearly show the attachment. Bolts 11 are provided on the rear of the bowl in spaced relation and serve to hingedly connect the seat member 9 to the bowl so that it may be swung upwardly in the usual manner, and these bolts also are utilized for mounting and securing the attachment in position.

The attachment is shown in enlarged detail in Figs. 3 to 7 inclusive, and comprises a shell 12 preferably in the form of a casting having laterally projecting lugs 13 cast integral therewith, and openings 14 are provided in the lugs, said openings being in direct alignment with the seat bolts 11 which extend therethrough to secure the shell in position.

The shell 12 is hollow as shown, the front end being open as indicated at 15, and a gate 16 forms a closure for said opening, said gate being pivotally mounted at 17 to admit foul air when in open position, and lugs 18 are provided in the shell for limiting the swinging movement of the gate, a coil spring 19 being attached to the shell and gate respectively, and serving to normally hold the gate in closed position. A pipe 21 is connected to the bottom face of the shell, a conduit 22 leads from said pipe to an exhaust line 23 so that the odors will be exhausted when the device is in operation.

A suitable switch 25 is mounted on the shell 12 in position as shown, and a spring pressed plunger or contact 26 projects from the face thereof, this switch controlling the exhaust fan 24, and wires 27 are connected to said switch, leading through the hollow shell and conduit 22 to the fan, similar wires 28 leading from the switch to a conventional socket (not shown) or other source of power.

The switch 25 can be manually actuated as indicated in Figs. 1 and 2 of the drawings, or it can be automatic as indicated in Fig. 8 and as will be presently described.

A bracket 29 is bolted or otherwise secured to the face of the shell 12, the upper end terminating in an elongated bearing 30, and a horizontally disposed shaft 31 is journaled therein. A switch actuating lever 32 is mounted on the shaft 31 with its free end in intimate contact with the end of the plunger 26, and a hand control lever 33 is mounted on the opposite end of said shaft so that the lever 32 may be swung to actuate the plunger 26 and energize the switch to operate the exhaust fan.

The gate 16 is simultaneously operable with the switch 25, a lever 34 being mounted on the shaft 31, and a shorter lever 35 being mounted on the shaft 17, a link 36 connecting the levers 34 and 35 so that actuation of the control lever 33 to operate the switch, also simultaneously actuates the gate 16.

This attachment can be very easily attached and makes a very neat installation, there is no cutting, fitting, or alteration; the seat bolts 11 hold it securely in position; the wires 27 are concealed from view; and the control handle is conveniently located.

In use, the operator merely swings the control lever 33 so that the levers 32 and 34 force the plunger 26 inwardly to energize the switch 25 which starts the exhaust fan 24 and also opens the gate 16 simultaneously, so that air may be exhausted from the bowl, and when the lever 33 is released, the spring pressed plunger 26 is forced outwardly, breaking contact and cutting off the current, and the linkage and spring 19 swing the gate 16 back to a closed position; thus making for economy in operation.

When the bowl 8 is arranged in a battery, such as is common in hotels and similar institutions, the exhaust fan and lines 23 and 24 respectively serve the entire battery, therefore, if no gate were provided, air would be drawn from all of the bowls in the battery even if one bowl only were in use, which would be both wasteful and inefficient.

In the arrangement shown in Fig. 8, the exhaust fan is automatically energized, a short bracket 38 being secured to the lower face of the seat 9 and is positioned to engage the switch plunger member 26 when the seat is down. Bumpers 39, made of rubber or similar material, are provided on the lower face of the seat in spaced relation, and spring members 40 are also provided as shown; these members serving to swing the seat upwardly to position shown in broken lines in Fig. 8 of the drawings when the toilet bowl is not in use, thus swinging the bracket 38 out of engagement with the plunger 26, and cutting off the supply of electric energy to the exhaust fan.

When the bowl is occupied, the seat is forced downwardly so that the bracket 38 actuates the plunger 26 to again energize the exhaust fan.

From the foregoing, it will be obvious that I have perfected a very simple, practical, and inexpensive ventilating attachment for toilet bowls which can be readily manufactured, assembled, and mounted, and which is efficient in operation.

What I claim is:

1. The combination with a toilet bowl having a hinged seat of a ventilating attachment adapted to be mounted on the bowl and comprising a flat, hollow shell, open at one end and having projecting lugs provided with openings in alignment with the openings for the bowl seat bolts and secured thereby, an exhaust pipe communicating with the lower face of the shell and leading to an exhaust fan, a switch housing and switch mounted on the upper face of the hollow shell and spaced rearwardly from the front edge of said shell, a spring pressed contact plunger projecting from the front wall of the switch housing, said switch being connected to the exhaust fan and to a source of power, a gate normally forming a closure for the open end of the shell, a horizontally disposed, manually operable shaft journaled on the housing, and levers on said shaft for opening said gate and engaging said plunger to energize said switch when the shaft is actuated.
2. The combination with a toilet bowl having a hinged seat, of a bowl ventilating attachment adapted to be mounted on the toilet bowl and comprising a hollow flat shell open at one end and having outwardly projecting lugs provided with openings in vertical alignment with the openings for the toilet bowl seat bolts and secured thereby, a shaft spanning the open end of the shell, a spring retracted gate mounted on the shaft and normally forming a closure for the open end of the shell, a lever on said shaft, an exhaust pipe opening into and connected to the lower face of the shell and leading to an exhaust fan, a switch housing and switch mounted on the upper face of the hollow shell and connected to a source of power and to an exhaust fan, a horizontally disposed spring pressed plunger projecting from the front of the switch housing, a vertically disposed, detachable bracket mounted on said shell, a bearing on the upper end thereof, a horizontally disposed shaft journaled in said bearing, a hand lever mounted on said shaft, a depending contact arm on said shaft for engagement with the spring pressed plunger when the arm is actuated to swing the lower flat end of the contact arm into engagement with the plunger to energize said exhaust fan when the shaft is actuated, and a second lever mounted on said shaft and connected to the gate shaft lever for simultaneously actuating said gate when the hand lever is actuated.
